DRAFT CONTROL

Edward A. Field, Jr., Mendota, Ill.

Application August 3, 1942, Serial No. 453,400

22 Claims. (Cl. 236—45)

This invention relates to improvements in draft controls.

The main objects of this invention are:

First, to provide an improved automatic draft control device for combustion heaters, stoves and the like which are entirely dependent upon natural draft for their air supply.

Second, to provide an automatic thermally responsive draft control which is responsive to the temperature of the flue gases of the heater to effect regulation of the draft in accordance with said temperature, appropriately increasing the draft when the flue temperature rises and decreasing the draft when the temperature falls.

Third, to provide a draft control of the type described, preferably for oil burning space heaters, which is effective to closely regulate the draft of said heaters in accordance with the flue temperature, thereby preventing wasteful combustion on the one hand due to excessive draft and accumulation of soot on the other due to too low draft, and at the same time affording requisite increased drafts for high burning rates which result in high fuel temperatures.

Fourth, to provide a device of the type described which is highly sensitive in its operation, having provision for counteracting or neutralizing factors normally tending to affect the accuracy of its operation, and which is simple and inexpensive in its parts notwithstanding its sensitivity.

Fifth, to provide an automatic temperature controlled draft regulator of the type described which has provision for maintaining the draft at values proportionate to the flue temperature, regardless of differences in the rate of increase thereof at differing temperature ranges, for a given fuel consumption.

Sixth, to provide an automatic, thermally controlled device of the type described including a bimetallic temperature responsive element positioned relative to the flue so as to be subject to the temperature of the flue gases and likewise in such manner as to withstand destructive action thereon of the sometimes exceedingly hot flue gases.

Seventh, to provide an automatic control of the type described which positively limits the draft at a predetermined desired minimum value, regulating the draft proportionally to the increasing flue gas temperatures up to a maximum, at which the draft is likewise positively limited.

Eighth, to provide a regulator of the type described including a thermally responsive element and mechanism actuated thereby to vary the resistance to movement of a counterweighted

gate, in which the regulating action is exerted on the gate in a manner to be consistent with the action of the counterweight on the gate, with resultant improved and more accurate operation.

5 Further objects relating to details and economies of the invention will definitely appear from the description to follow. The invention is defined in the claims.

A structure embodying the features of this invention is clearly illustrated in the accompanying drawings, wherein:

Fig. 1 is a fragmentary view in front elevation illustrating my invention as embodied in an oil burning natural draft space heater, the elements 15 of the control being illustrated in their position for minimum flue gas temperature and the draft control gate being shown in partially closed position.

Fig. 2 is a view similar to Fig. 1, illustrating 20 the parts in position for maximum or increased temperature control, the draft control gate in this case being shown in fully opened position under the influence of air pressure thereon.

Fig. 3 is an enlarged fragmentary detail view 25 in section on a line corresponding to line 3—3 of Fig. 1 illustrating the thermally responsive actuating element of the control and details of mounting thereon the smoke flue.

Fig. 4 is an enlarged fragmentary view in section on a line corresponding to line 4—4 of Figs. 30 1 and 5, illustrating the structural details and the relationship of the parts of the control with the latter automatically positioned for minimum temperature operation.

Fig. 5 is a view partially broken away and in 35 horizontal section further illustrating structural details and relationships, with the control parts in the position illustrated in Figs. 1 and 4.

Fig. 6 is an enlarged fragmentary view in section on a line corresponding to line 6—6 of Fig. 2 illustrating further structural details and indicating the operation of the thermal element and parts connected thereto in solid and dotted lines respectively.

45 Fig. 7 is an enlarged fragmentary detail view in section on a line corresponding to line 7—7 of Fig. 5 illustrating provisions for preserving accuracy and maximum sensitivity in the movements of the control mechanism.

Fig. 8 is a fragmentary perspective view partially broken away and in section illustrating a detail of the gate mounting and stop means of the control.

50 Fig. 9 is a fragmentary view in section on a line

corresponding to line 9-9 of Fig. 1 further illustrating details of the gate pivot structure, and

Fig. 10 is a fragmentary top plan view partially broken away and in horizontal section illustrating a modified structure incorporating the invention.

The present invention relates to an automatic thermally controlled draft regulator well adapted for the regulation of oil burning space heaters of the type dependent entirely upon natural draft for their air supply. Most such heaters can be operated at burning rates which vary from a maximum down to a minimum of only 20% or 25% of the maximum rate. It is desirable that at the lower burning rates only a comparatively small amount of air shall be supplied to the burner; however, it is a very rare occurrence when the operator takes the trouble to alter the setting of the draft control of the heater for each change in the position of the fuel control valve. Manufacturers have heretofore provided draft controls with adjustments appropriately marked and settable to correspond to similar fuel consumption markings on an oil dial, but the results are still not satisfactory. The operator usually neglects to change the draft setting and simply manipulates the oil control dial up or down to regulate the fuel supply. This is objectionable, for excessively high drafts waste fuel and excessively low drafts cause accumulation of soot.

An attempt has been made to overcome this difficulty by permanently setting the draft control for a rather high draft; for example, a draft which is about right for a burning rate of 80% or 90% of maximum, but the fact remains that this draft is still a trifle too low for the maximum combustion rate and a great deal too high for medium or low burner settings. Most oil burning heaters are operated at a medium or low oil setting the majority of time, which means a great deal of fuel is needlessly wasted by excessive draft when the latter is set in the manner referred to.

The device of the present invention consists of a draft control having applied thereto a thermally controlled apparatus which is sensitive or responsive to flue gas temperature to automatically regulate the draft settings according to the temperature of the gases in the flue as discharged from the heater. With this invention I increase the draft when the temperature in the flue rises and decrease the draft when the temperature in the flue falls. This is a marked departure from the operation of most thermally controlled regulators, which reduce the draft when the temperature rises and increase the draft when the temperature falls. In the present invention I take advantage of the fact that fuel temperatures increase with higher burning rates so as to provide increased drafts for such higher burning rates, inasmuch as the present device is operative in response to fuel temperatures in direct relation thereto.

Generally stated, the device effects the foregoing operation by an adjustable compensating weight appropriately connected to the draft control gate, which in the illustrated embodiment is a counterweighted one, and swingable to vary the resulting torque stresses on the gate as the temperature of the flue gases varies, in such manner as to compensate or variably counteract the torque of the gate on its pivots. As the temperature increases the compensating or counteracting effect decreases. At and below the minimum flue gas temperature the adjustable weight is located in a position and has its torque ap-

plied to the gate in a manner such that it counteracts to a maximum extent the torque of the gate counterweight and thereby renders the gate least resistant to oppose the flow of air therethrough into the flue. It will be appreciated that a temperature sensitive mechanism of this compensating type is applicable to various types of draft control to automatically regulate the setting thereof in accordance with flue gas temperature. In my copending application Serial No. 453,402, filed concurrently herewith, Patent No. 2,358,390, Sept. 19, 1944, I illustrate the mechanism associated with a well-known blocking type control. Further details of the operation of the structure chosen for illustration herein and of the principle embodied in the invention, generally considered, will become apparent as the description of the structure proceeds.

Referring to the drawings, the reference numeral 1 designates an oil burning space heater of a type which is dependent entirely upon natural draft. The reference numeral 2 in general designates the draft control employed in the present embodiment of this invention, which is housed in and supported by a pipe 7, arm 3 of which is applied directly to the smoke outlet of the heater 1 and serves in the manner of a smoke flue; hence it will be referred to as such. This control device will also operate correctly if the tee is located so as to constitute the second or third length of the flue from the stove, with appropriate calibration of the device for such a mounting.

The outwardly projecting leg 4 of the T constitutes a cylindrical draft control housing, being provided at its outer end with an annular stamped sheet-metal gate frame 5 disposed in and abutting said outer end. The frame has a gate opening 6 therein, preferably straight-sided, provided with laterally inwardly extending flanges or wings 8 in spaced relation to the adjacent sides of the housing 4 (see Figs. 8 and 9). The draft control gate 10 disposed in opening 6 also has parallel rearwardly extending flanges 11 formed on the sides thereof adjacent wings 8, and a pintle rod 12 secured eccentrically to the gate and extending through apertures in said gate flanges 11; serves to provide pivot trunnions 13 for the gate. The said housing wings 8 adjacent the forward end of the latter are provided with elongated recesses 14 on the lower edge of which gate pivoting trunnions 13 are rollingly received to effect a very free frictionless journaling of the gate; while the radially extending side shoulder 15 of the gate frame immediately to either outer side of wings 8 has lips or lugs 16 struck rearwardly therefrom parallel to said wings which act as end abutments preventing excessive longitudinal or endwise movement of the gate trunnions.

As illustrated in Fig. 8, the gate flange 11 on one side of the gate is slit and conformed to provide a spring stop finger 17 which projects laterally outwardly through an arcuate opening 18 provided in the housing flange or wing 8. By engaging the opposite angular limits of said opening 18 the spring stop 17 limits the swinging of the gate at its closed and maximum open positions. This is performed effectively and silently, due to the resilient character of stop 17.

The smoke flue 3 intermediate the heater 1 and the control housing 4 is provided with a horizontally elongated opening 18 by the expedient of slitting the side wall thereof horizontally and offsetting outwardly to provide a pair of

parallel flanges 20 from the material thereof. Within this opening I mount a blade-like bimetallic thermal element 21, see Figs. 1, 2, 3 and 6. This thermal element is fixedly secured at one end to the side of the flue through its engagement by lugs 19 and 22 on the latter. At its other end the thermal element is secured as by the rivets 221 to the laterally disposed end 23 of an angled actuating arm 24, this arm being angled as shown in Fig. 1 so that its outer end is positioned below the housing 4 as is clearly shown in the drawings. The portion 23 of the arm is provided with ears 231 receiving the pivot 25 carried by the flanges 20, see Figs. 1 and 3.

The thermal element 21 is disposed with its high-expansive side on the outer side of the flue and exposed to the air in the room being heated. This is advantageous because of the fact that the thermal element thus does not become undesirably heated as is likely to be the case where it is entirely surrounded by the hot gases in the flue. A slight amount of air leaks in around the cracks at the edges of the thermal element and tends to further cool the same. Thus an ordinary comparatively inexpensive bimetallic blade-like member will serve my purpose, whereas, if the latter were disposed entirely within the flue and surrounded by gases, the temperature of which reaches 900 or 1000 degrees F., a very special grade or design of thermal element would be called for. It is evident that as the temperature in the flue increases the thermal element 21 warps or bows outwardly from the position indicated in solid to dotted line position, correspondingly swinging the actuating arm 23, and that under decreasing temperatures the reverse movement takes place.

Referring to Fig. 5, the control housing 4 has fixedly secured to its lower side a depending stop member 26 recessed on its lower edge at 27 to receive the arms 24, the ends of the recess constituting stops limiting the swinging movement of the arm under the influence of the thermal element. This provides a minimum draft position for the control, to be hereinafter referred to more fully, in which a predetermined pressure is exerted on the actuating arm and the thermal element 21, and likewise a predetermined position of maximum movement of the actuating arm under maximum flue gas temperature to which the control is responsive. This is desirable because, if an excessive temperature should prevail in the flue for some reason, the movement of the actuating arm 24 might be so great as to damage the parts of the device to be described.

At its outer end the arm 24 has adjustably mounted thereon an extension arm 28, a rivet 29 serving as a pivotal connection. Arm 24 and its extension 28 are fixedly secured to one another in appropriately adjusted position by means of a screw 30 threadedly received by the arm 24 and extending through a slot 31 in extension 28 with its head bearing against the latter (see Figs. 2 and 5). This permits relative adjustment of the actuating arm and its extension for minimum draft positioning of the gate 10. Assuming that a minimum draft of .02 inch is desired, the extension 28 is appropriately set so that the parts actuated by said arm (to be described) are positioned and exert appropriate action on the gate. Instruments are employed to ascertain the value of the draft and adjustment of the arm parts is made accordingly.

Referring now to Figs. 1, 4 and 5, the control

housing 4 has depending therefrom a sheet metal supporting frame or bracket 32 provided with an opening to receive arm 24 for free swinging movement. Bracket 32 has V notch openings 33 in its opposite side walls receiving knife edge pivots 34 which are turned outwardly from a stirrup-like U shaped rocker member 35. This U shaped rocker member 35 has rigidly secured to one of the parallel arms thereof a forwardly projecting gate compensating control arm 36 and said arm has as an integral part thereof a pair of out-turned upper and lower ears 37, 38 located rearwardly of the knife edge pivots 33, said ears serving to receive a vertical pivot pin 39. The lower end of this pin is rounded to minimize friction in its turning and rests on the cross member 40 of the rocking member 35 (see Fig. 7). Pin 39 has secured thereto a laterally oscillatable compensating weight swing arm 41. This pin has a free, frictionless pivotal movement in the journaling ears 37, 38 therefor and the swing arm 41 is secured fixedly to said pin for movement therewith. At its outer end the lever is offset upwardly at 42, bringing the upwardly offset portion into a plane which includes the pivot point of knife edges 34. Appropriate, preferably equal-sized, compensating weights 43, 44 are mounted on the upper and lower sides of arm portion 42 so that their center of gravity 30 lies in this plane.

By reference to Fig. 5 it will be noted that compensating weight swing arm 41, which is of sheet metal material, has its pivot pin 39 secured thereto at one inner corner thereof. Adjacent the opposite inner corner, or at least in substantially spaced relation to pin 39, arm 41 is provided with an upwardly and forwardly turned ear 45 for effecting a pivotally actuating connection between the swing arm and a link 46 by which the same is actuated from the actuating arm extension 28. Link 46 is pivoted at its opposite end to said extension.

In effecting the aforesaid pivotal connections of link 46 to the arm 41 and actuating arm extension 28, respectively, the link is provided with concave, rounded anti-friction bearing portions 47, 48 adjacent either end thereof and projecting in the same direction, i. e., downwardly from the plane of the link. These bearings rest respectively on the swing arm ear 45 and on the arm extension 28. The bearings are provided with openings 49 for the reception of the pivot pins 50, 51. Pin 50 extends downwardly through aligned openings in swing arm 41 and the ear 45 thereon, while pin 50 is received in an opening in the arm extension 28. The purpose of the convex bearings 47, 48 is to reduce the friction between the parts when the actuating extension 28 is rocked horizontally, also permitting vertical rocking or tilting movement of the arm 41 without binding of the parts such as would detract from the sensitivity of the control. It will be noted by a reference to Fig. 7 that the points at which the link bearings 47, 48 engage the swing arm 41 and the actuating arm extension 28, respectively, lie in a plane passing through the pivot point of the knife edges 34. The purpose of this arrangement will be hereinafter referred to.

At its outer end the forwardly projecting gate compensating control arm 36, which as stated is rigidly secured to the rocking support 35 for vertical rocking movement therewith, has attached thereto a connector link 52 which extends upwardly through an opening 53 in the lower part of control housing 4 and is connected at its

upper end to a relatively short bracket 153 secured to the gate 16 on the rear side thereof. The point of pivotal connection of the link 52 to bracket 153 lies in a plane extending through the gate pivot 13 at an angle of approximately 70 degrees to the gate. The gate itself is provided beneath its pivot point with a pair of counterweights 54, 55 on the outer and inner sides thereof, respectively, the weight 54 being fixed and the weight 55 being eccentrically mounted on an attaching screw 56 for adjustment at the factory. However, after installation no further adjustment of this weight is contemplated.

Although the operation of the device will be hereinafter explained in greater detail, it may be generally stated that it is the function of the swingable compensating weights 43, 44 on arm 41 to variably compensate or counteract the torque of counterweights 54, 55 on the gate in accordance with the temperature of the flue gases, and thereby render the gate more resistant to opening under the external pressure of air thereon as the temperature increases and less resistant to opening as the temperature decreases. It will be understood that the combined weights 54, 55 in combination with the weight of the gate 16 itself will, when properly adjusted, produce a predetermined closing torque effective on the gate.

In actual manufacture, after the factory balancing operation is completed, the center of gravity of all of the gate carried parts will be located in a plane passing through the gate pivot point outwardly and downwardly at an angle of 70 degrees to the plane of the gate, and it is essentially important, in accordance with the present invention, that the effect of the compensating provisions carried by the rockable support and connected to the gate shall be applied on the latter in the same manner as the fixed counterweights 54, 55. Consequently I have made particular provision that the link 52 shall connect to the gate or bracket 153 thereon in the 70-degree plane referred to.

In actual practice the gate is permitted by the stop 17 and limit opening 181 to open about 80 degrees from its closed position and although the center of gravity is located in a plane extending downwardly a slight degree when the gate is closed or in vertical position, nevertheless throughout the greater part of the swing or movement of the gate the center of gravity of the combined gate parts moves upwardly and over toward the vertical plane of the gate, there being only about 20 degrees of gate movement (at the time the latter starts to open) when the center of gravity moves away from the vertical plane of the gate. This is consistent with principles which I have found to be sound.

In practice the normal weight on the gate is chosen so that there is sufficient closing force effective thereon to maintain the desired minimum draft, say .07 or .08 inch of draft. The compensating weights 43, 44 are so chosen and applied to the compensating weight swing arm 41 that when the latter is in its extreme forward position for minimum draft and temperature control, as illustrated in Figs. 1, 4 and 5, a torque will be exerted on the rocking support 35 in a clockwise direction as viewed in Fig. 5, which is of sufficient magnitude to offset or neutralize most of the aforesaid counterweight closing torque on the gate, leaving a net difference of only the amount necessary to close the gate against the desired minimum draft, assumed to

be .02. As the bimetallic strip 21 warps and bows outwardly under increasing flue gas temperature due to an increase in the fuel consumed, actuating arm 36 is rotated counterclockwise about pin 38, as viewed in Figs. 5 and 6, from solid toward dotted line position in the latter, being thereby effective through extension 28, link 46 and arm 41 to swing the weights 43, 44 rearwardly or in clockwise direction as viewed in Fig. 5.

As weights 43, 44 approach the vertical plane passing through the knife edge pivots of the rockable support 35 the torque exerted through wire link 52 becomes less, due to decrease in moment arm of the weights; hence the counteracting compensation of the fixed gate counterweights 54, 55 is diminished and the closing torque effective on the gate increased, requiring a greater draft to swing the same. In this connection it is pointed out that the link 52 may be attached to the front of the gate instead of the back if the action of the compensating weight swing arm 41 is reversed, and the same results accomplished. However, attaching the link to the front side of the gate would require offsetting or bending of the same to avoid being struck by the gate as the latter is opened. Hence, it is found more convenient to attach the link to the rear side of the gate.

In order to rigidify the flue 3 at its attachment to the heater, likewise to stabilize the bimetallic strip 21, I provide an internal strut 58 extending across between the two sides of the T. Also, in order to prevent the bimetallic strip from being unduly influenced by cool air entering and passing through the draft control housing 4, which air sometimes tends to eddy back into the flue toward the heater 1, I provide deflecting louvers 59 at the inner corner of housing 4 adjacent its union with the flue portion of the T. In the illustrated example these louvers consist of curved bands of metal arranged overlapping in such a manner as to tend to direct the air flow towards the chimney instead of striking the back side of the T and swirling in all directions. These louvers also assist in preventing disposition of soot in the draft control, but the primary purpose thereof as regards the present invention is to prevent the cold air from contacting or influencing or affecting the inner side of the thermal element. If this occurs, then on a day when the gate 16 has to be opened quite wide, as on a clear cold day, much more air will be passed into the pipe than would be the case on a warmer day, and consequently the most desirable action of the control device will not be had.

Referring to Figs. 4 and 5, it will be noted that the link actuating compensating arm 36 on the rocker support 35 has an added piece 57 affixed thereto constituting a counterbalance or counterweight for the rocking assembly. This weight is positioned on the arm 36 to counterbalance the weight of the other parts of the rocking assembly, so that when the compensating weights 43, 44 are removed and swing arm 41 is in the forward minimum draft position of Fig. 5 the combined parts are substantially in balance, with their combined center of gravity coincident with the axis of the rocker assembly, i. e., on a line passing through the knife edges 34 by which said assembly is pivoted.

While the rocking assembly does not swing more than five or six degrees to either side of the horizontal position of arm 36 as shown in Fig. 4, yet if the combined center of gravity were

considerably above or below the pivotal axis of the assembly, then, as the rocking support 35 rocked and the center of gravity was shifted over close to the vertical plane of the axis, the torque developed would vary considerably. To avoid this I have provided that the compensating weights 43, 44 are of the same size and weight and are disposed one above and one below the vertical offset end 42 of lever arm 41. This assures that the plane in which the outer portion of the arm swings and the center of mass of the two weights will pass through the pivotal axis of the rocker assembly, since, as has been pointed out, the offset in swing arm 41 disposes the end thereof in a plane passing through the pivot point of knife edges 34. The combined center of gravity of weights 43, 44 and arm 38 always rocks through the same part of a vertical arc, regardless of the lateral position of the compensating weight swing arm 41.

If the temperature of the flue gas increases, indicating the need for a greater draft for perfect combustion, the bimetallic strip 21 bows outwardly from solid line position of Fig. 6 toward the dotted line position, rocking the actuating arm 24 which is rigidly secured thereto in counterclockwise direction as viewed in Figs. 5 and 6, so that link 46 is thrust under compression to the left in Fig. 5 and thereby pivoting swing arm 41 in clockwise direction as viewed in Fig. 5. This thermally derived force is transmitted accurately and proportionately regardless of the position of the gate 10, and hence of the rocking assembly on which the force transmission link 46 is carried, due to the provision of the rounded bearings 47, 48 on the link at the points of its pivotal connection to actuating arm extension 28 and the swing arm 41. The holes in said link receiving the pivot pins 50, 51 are sufficiently large so that the rocker assembly can swing up or down 8 or 10 degrees without any appreciable binding action such as would detract from the accuracy or sensitivity of the device.

I have pointed out above the aforesaid link pivotal points or bearings are in a plane passing through the pivotal axis of the rocking assembly at knife edges 34 (see Fig. 7). It will be further noted by reference to this last figure that the point where the link is pivoted to the actuating arm extension 28 is very close to said rocker assembly axis at knife edges 34, hence, as arm 24 and extension 28 swing to the rear in compensating to provide increased draft, the link pivot to extension 28 passes by a short movement through the rocker assembly axis and beyond the same a slight distance on the other side thereof. By making the distance traversed by the pivot link connection on either side of the rocker assembly axis comparatively small, the accuracy of the device is considerably contributed to. If link 46 were attached to extension 28 at a relatively great distance from the knife edge axis of the rocking assembly, then as the latter rocked back and forth the change in angles would necessarily cause considerable lateral movement of the compensating weight swing arm 41. However, when the link pivot to arm extension 28 is closely adjacent the rocker assembly pivot axis in any position of said extension there is substantially no horizontal swinging of the arm 41 due to the vertical rock of the rocking assembly. In other words, said assembly is rocked only in response to preponderating pressure of air on gate 10, rather than the possibility of rocking the same accidentally due to the movement of the actuat-

ing arm 24 and extension 28 thereof. The latter should, and in the arrangement as described does, only function to position the compensating weights 43, 44 in accordance with the flue gas temperature so that said compensating weight may accurately exert its proportional compensating effect on the counterweighted gate.

As compensating weights 43, 44 are swung to the rear in clockwise direction under the influence of increasing flue temperature, they become, as stated, decreasingly effective in their ability to offset the action of the main gate counterweights 54, 55, with resultant increase in the resistance of gate 10 to swinging and production of a higher draft for the heater 1. This swinging movement continues to a maximum draft position so far as the control is concerned, in which actuating arm 24 strikes the stop 27. Further excessive increase in the temperature due to an abnormal combustion condition is thereafter ineffective in moving the compensating weights, with attendant possible damage to the more delicate parts of the device.

It is a well-known fact that operating characteristics of different stoves are not the same. With some stoves or heaters the rise in flue gas temperatures as the fuel consumption is increased, is approximately a straight line, while with others it is in the form of a curve. This may be allowed for in the present device by changing the point of attachment of the link 46 to the swing arm 41, also by changing the position of the said swing arm at its initial starting position for low draft, using the adjustment described above. Thus the swing arm can be made to rotate through different parts of the arc for different stoves or heaters, and the number of degrees of rotation may also be varied. Also, if the size of the weights 43, 44 is changed the torque developed can be made to conform approximately to the requirements of practically any stove.

As will be apparent from an inspection of Fig. 5, the change in torque exerted by weights 43, 44 is relatively small as the arm 41 first starts to swing away from its position in that figure, there being little movement toward the rocking assembly axis, but as the arm 41 approaches its other extreme position the change in torque is quite rapid for each degree of swing. This offsets the fact that flue gas temperatures rise more rapidly as the fuel feed is increased from a low setting than is true after the stove is already operating at a fairly high burning rate. To illustrate this, in a given type heater, if the oil feed is increased from 7 cc. per minute to 14 cc. per minute, the flue gas temperature may increase as much as 200 degrees F., but when the oil feed is changed a similar amount from 21 cc. to 28 cc. per minute the flue gas temperature may increase only 100 degrees F. Therefore, it will be appreciated that my control is sensitive to this non-linear relation fuel feed to flue temperature to insure the supply of adequate yet not excessive air to the heater, in proportion with the air requirements for most efficient combustion. Under the conditions stated the draft at the lower rate of fuel consumption is maintained proportionately low and at the high rate of consumption is maintained proportionately high, notwithstanding the fact that the ultimate adjustment of the mechanism itself, i. e., the angular swing of arm 41, is linearly responsive in proportion to the changes in flue gas temperatures.

In Fig. 10 I have illustrated a modified adaptation of the invention, similar to the foregoing

in all respects, save that the actuating arm 24 (or appropriate adjustable extension thereon, not shown) is effective on the compensating weight swing arm 41 by a camming action instead of the linkage arrangement illustrated in the preceding figures. In this embodiment arm 24 is provided with a lug or pin 60 engaging the cam slot 61 which is provided in the swing arm 41 in spaced relation to its pivot 39. The arms 24 and 41 are swing from solid to dotted line position in the manner illustrated, as the bimetallic strip 21 bows under increasing flue gas temperature and reversely under decreasing temperature, by cam engagement of lug 60 with opposite sides of the cam slot 61 as will be readily appreciated.

Further modifications incorporating the principles discussed at length above will readily suggest themselves to those skilled in the art. Thus different forms of thermally responsive element connected to the rocking support 35 in appropriate fashion will procure a similar result, if the broad concepts explained above are adhered to. Similarly various alternative methods of applying the compensating torque to the gate will suggest themselves. I find that the construction defined herein is very satisfactory in operation, however.

The above described control is extremely sensitive and reliable in automatically effecting draft regulation in proportion to the temperature of the flue gases. The parts are simple and the relationships are such that departures from strict accuracy due to the mechanical movements thereof are minimized to such an extent as to be negligible. By contrast to heretofore known thermally controlled devices which operate inversely to reduce draft upon increase in the flue gas temperatures, my device maintains a direct proportion therebetween, within certain definite predetermined chosen maximum and minimum draft conditions, which may be selected as desired upon installation. Of course, high burning rates produce high fuel temperatures and my device takes advantage of this fact to provide increased drafts for the higher burning rates, with the resultant improved efficiency, since it is responsive to the flue temperature. Use shows that a very close correspondence exists in the proportion between fuel consumption and the flue gas temperature on the one hand and the draft as regulated by my device on the other hand, with highly desirable combustion indeed under all operating conditions as reflected by CO₂ analysis.

I have illustrated and described my invention in embodiments which have been found to be very satisfactory in operation. I have not attempted to illustrate or describe other embodiments or adaptations which I contemplate as it is believed this disclosure will enable those skilled in the art to embody the invention as may be desired.

Having thus described the invention what I claim as new and desire to secure by Letters Patent is:

1. An automatic thermally responsive draft control device comprising in combination with a heater flue, a draft control housing communicating with said flue provided with a pivoted draft control member subject to air pressure externally of the housing and normally biased to resist movement under said pressure, a rocker member pivotally supported for vertical rocking movement and operatively connected to said draft control member whereby rocking torque of said rocker member is effective to modify the bias on said

control member resisting movement thereof, a compensating swing arm pivoted on said rocker member for lateral swinging movement at right angles to the plane of rocking movement of the member, a compensating weight carried by said swing arm, the center of gravity of the swing arm and weight traveling laterally in a plane including the pivotal axis of said rocker member to alter the moment arm of said compensating weight and thereby vary the torque of said rocker member, and means for variably positioning said swing arm and compensating weight in accordance with the temperature in said flue to thereby regulate the bias on said draft control member, comprising a thermally responsive bimetallic element positioned adjacent said flue and subject to the flue gas temperature therein, an actuating arm pivoted adjacent said flue, said element being secured at one end thereof to the flue and at the other end thereof to said actuating arm, whereby movement of said element in response to changes in the flue temperature results in swinging of the actuating arm around its pivot, and a link eccentrically pivoted to said swing arm and pivoted to the free end of said actuating arm for actuation of the swing arm and compensating weight in response to thermal changes in the flue, said link pivot points lying in a plane including the pivotal axis of the rocker member.

2. An automatic, thermally responsive draft control device, comprising in combination with a heater flue, a draft control housing communicating with said flue provided with a pivoted draft control member subject to air pressure externally of the housing and normally biased to resist movement under said pressure, a rocker member pivotally supported for vertical rocking movement and operatively connected to said draft control member whereby rocking torque of said rocker member is effective to modify the bias on said control member resisting movement thereof, a compensating swing arm pivoted on said rocker member for lateral swinging movement at right angles to the plane of rocking movement of the member, a compensating weight carried by said swing arm for lateral movement to alter the moment arm of said compensating weight and thereby vary the torque of said rocker member, and means for variably positioning said swing arm and compensating weight in accordance with the temperature in said flue to thereby regulate the bias on said draft control member comprising a thermally responsive element positioned adjacent said flue and subject to the flue gas temperature therein, an actuating arm pivoted adjacent said flue, said element being secured to said actuating arm whereby movement of said element in response to changes in the flue temperature results in swinging of the actuating arm around its pivot, and a link eccentrically pivoted to said swing arm and pivoted to the free end of said actuating arm for actuation of the swing arm and compensating weight in response to thermal changes in the flue.

3. In combination with a heater smoke flue discharging combustion gases, a draft control housing communicating therewith at one end and at its other end provided with an air admission opening and a counterweighted gate eccentrically pivoted in the opening, said gate being normally subject to torque tending to resist opening movement of the gate in response to external air pressure thereon, a thermally responsive element located adjacent and subject to the temperature in the flue, a pivoted actuating arm connected

to said element and pivotally actuated thereby in response to thermally induced movement of the latter, a rocker member mounted for vertical swinging movement and operatively connected to said gate whereby rocking torque of said member is transmitted to the gate to alter the torque normally effective thereon, a swing arm pivoted on said rocker member having a compensating weight thereof, a link pivotally connected eccentrically to said swing and actuating arms respectively to transmit thermally induced movement of the latter to the former and thereby vary the moment arm of the compensating weight relative to the pivotal axis of the rocker member, said compensating weight, depending on its moment arm relative to the pivotal axis of said rocker member, being effective through said rocker member and connection thereof to the gate to exert greater or less compensating effect on the torque on the gate tending to resist movement of the latter, and means to limit the movement of said actuating arm at opposite extremes thereof.

4. In combination with a heater smoke flue discharging combustion gases, of a draft control housing communicating therewith at one end and at its other end provided with an air admission opening and a counterweighted gate eccentrically pivoted in the opening, said gate being normally subject to torque tending to resist opening movement of the gate in response to external air pressure thereon, a thermally responsive element located adjacent and subject to the temperature in the flue, a pivoted actuating arm connected to said element and pivotally actuated thereby in response to thermally induced movement of the latter, a rocker member mounted for vertical swinging movement and operatively connected to said gate whereby rocking torque of said member is transmitted to the gate to alter the torque normally effective thereon, a swing arm pivoted on said rocker member having a compensating weight thereof, means operatively connecting said swing and actuating arms respectively to transmit thermally induced movement of the latter to the former and thereby vary the moment arm of the compensating weight relative to the pivotal axis of the rocker member, said compensating weight, depending on its moment arm relative to the pivotal axis of said rocker member, being effective through said rocker member and connection thereof to the gate to exert greater or less compensating effect on the torque of the gate tending to resist movement of the latter.

5. In an automatic thermally responsive draft control device, in combination with a heater smoke flue adapted to be traversed by combustion gases, a draft control housing communicating therewith at one end and at its other end provided with an air admission opening and a counterweighted gate eccentrically pivoted in the opening, said gate being normally subject to torque tending to resist opening movement of the gate in response to external air pressure thereon, a thermally responsive element subject to the temperature in the flue between said control housing and the heater to which the flue is connected, a pivoted actuating arm connected to said element and pivotally actuated thereby in response to thermally induced movement of the latter, a rocker member mounted for vertical swinging movement and operatively connected to said gate at a point in a plane including the gate pivotal axis and the center of gravity of the counterweighted gate, whereby rocking torque of

5 said member is transmitted to the gate to alter the torque normally effective thereon, a swing arm pivoted on said rocker member having a compensating weight thereon swingable laterally with said arm in a plane including the pivotal axis of the rocker member, and a link pivotally connected eccentrically to said swing and actuating arms respectively to transmit thermally induced movement of the latter to the former and thereby vary the moment arm of the compensating weight relative to the pivotal axis of the rocker member, the pivotal points of connection of said link to said arms lying in a plane passing through the pivotal axis of the rockable member, said compensating weight, depending on its moment arm relative to the pivotal axis of said rocker member, being effective through said rocker member and connection thereof to the gate to exert greater or less compensating effect on the torque on the gate tending to resist movement of the latter, and means to limit the movement of said actuating arm at opposite extremes thereof.

6. In combination with a heater smoke flue discharging combustion gases, a draft control housing communicating therewith at one end and at its other end provided with an air admission opening and a counterweighted gate eccentrically pivoted in the opening, said gate being normally subject to torque tending to resist opening movement of the gate in response to external air pressure thereon, a thermally responsive element located adjacent and subject to the temperature in the flue, an actuating member connected to said element and actuated thereby in response to thermally induced movement of the latter, a rocker member mounted for vertical swinging movement and operatively connected to said gate whereby rocking torque of said member is transmitted to the gate to alter the torque normally effective thereon, a compensating weight shiftably mounted eccentrically on said rocking member, and means operatively connecting said weight to said actuating element to transmit thermally induced movement of the latter to the former and thereby vary the moment arm of the compensating weight relative to the pivotal axis of the rocker member, said compensating weight, depending on its moment arm relative to the pivotal axis of said rocker member, being effective through said rocker member and connection thereof to exert greater or less compensating effect on the torque on the gate tending to resist movement of the latter.

7. In combination with a heater smoke flue discharging combustion gases, a draft control housing communicating therewith at one end and at its other end provided with an air admission opening and a counterweighted gate eccentrically pivoted in the opening, said gate being normally subject to torque tending to resist opening movement of the gate in response to external air pressure thereon, a thermally responsive element located adjacent and subject to the temperature in the flue, an actuating member connected to said element and actuated thereby in response to thermally induced movement of the latter, a rocker member operatively connected to said gate whereby rocking torque of said member is transmitted to the gate to alter the torque normally effective thereon, a compensating weight shiftably mounted on said rocking member, and means operatively connecting said weight to said actuating element to transmit thermally induced movement of the latter to the

former and thereby vary the moment arm of the compensating weight relative to the pivotal axis of the rocker member, said compensating weight, depending on its moment arm relative to the pivotal axis of said rocker member, being effective through said rocker member and connection thereof to exert greater or less compensating effect on the torque on the gate tending to resist movement of the latter.

8. An automatic thermally responsive draft control device comprising, in combination with a heater flue, a draft control housing communicating with said flue provided with a rotatable draft control member subject to air pressure externally of the housing and normally biased to resist rotative movement under said pressure, a rocker member mounted for vertical rocking movement and operatively connected to said draft control member so that vertical movement of said rocker member is effective to modify the bias on said control member resisting movement thereof, a compensating weight swing arm pivoted on said rocker member for lateral swinging movement of the member, a compensating weight carried by said swing arm, the swing arm and weight swinging laterally to alter the moment arm of said compensating weight on the rocker member and thereby vary the torque exerted by said rocker member, and means for variably positioning said swing arm and compensating weight in accordance with the temperature in said flue to thereby regulate the bias on said draft control member, comprising a thermally responsive element subject to the temperature of gases which are discharged to the flue, actuating means connected to said element for operation thereby in response to changes in the flue gas temperature, means operatively connecting said actuating means to said swing arm for swinging movement of the compensating weight in response to thermal changes in the flue gas, thereby altering the torque applicable through said rocker member on said draft control member.

9. An automatic thermally responsive draft control device comprising, in combination with a heater flue, a draft control housing communicating with said flue provided with a rotatable draft control member subject to air pressure externally of the housing and normally biased to resist rotative movement under said pressure, a rocker member operatively connected to said draft control member so that vertical movement of said rocker member is effective to modify the bias on said control member resisting movement thereof, a compensating weight shiftably mounted on said rocker member to alter the moment of said compensating weight on the rocker member and thereby vary the torque exerted by said rocker member, and means for variably positioning said compensating weight in accordance with the temperature in said flue to thereby regulate the bias on said draft control member, comprising a thermally responsive element subject to the temperature of the gases which are discharged to the flue, actuating means connected to said element for operation thereby in response to changes in the flue gas temperature, and means operatively connecting said actuating means to said compensating weight in response to thermal changes in the flue gas, thereby altering the torque applicable through said rocker member on said draft control member.

10. An automatic thermally responsive draft control device, comprising in combination with a

heater flue, a draft control housing communicating with said flue provided with a swingable draft control member subject to air pressure externally of the housing and normally biased to resist movement under said pressure, a rocker member mounted for vertical rocking movement and operatively connected to said draft control member so that rocking torque of said rocker member is effective to modify the bias on said control member resisting movement thereof, a compensating weight shiftably mounted on said rocker member eccentrically of the axis thereof and shiftable relative to the axis to vary the moment arm of the weight and thereby regulate the torque of said rocker member, and means for variably positioning said compensating weight to proportion the closing bias on the control member in accordance with the temperature in said flue, comprising a thermally responsive element subject to the temperature of the gases which are discharged to the flue, an actuating member mounted adjacent said flue and connected to said element for actuation thereby upon operation of the element in response to changes in the flue gas temperature, and means operatively connecting said actuating member to said weight for shifting of the compensating weight in response to thermal changes in the flue gas.

11. An automatic thermally responsive draft control device comprising in combination with a smoke flue, a draft control housing communicating with the flue, means to prevent swirling of air entering said housing into said flue in the direction of the heater attached thereto, a draft control member pivoted in said housing subject to external air pressure, a thermally responsive bimetallic element disposed in an opening in said flue between the heater and housing and fixedly secured at one end to the flue, a pivoted actuating arm operatively connected to the other end of said element for swinging movement in response to thermal changes in the latter, a support secured to said housing, a compensating assembly comprising a rocker member pivoted on said support for vertical rocking movement having a compensating arm connected by a link to said draft control member, said rocker member being provided with a compensating weight positionable variably relative to the axis of the rocker member, and means connecting said weight to said actuating arm for shifting of the weight relative to the axis of rotation of the rocker member in response to changes in temperature in said flue.

12. In an automatic thermally responsive draft regulator, in combination with a flue member discharging products of combustion, a draft control device having a draft passageway communicating with the member, said device being provided with a draft control element having opening and closing movements in said passageway for regulating the flow of air therethrough to the member, said draft control element being mounted to be opened by excess of outside atmospheric pressure over inside flue pressure, means for resisting opening movement of said control element, said member having an opening therein in advance of the draft control connection thereto, a blade-like thermally responsive element located in said opening and secured at one end to the member so as to be subject on one side thereof to the temperature internally of the member and on the other side to the temperature externally of the member, and means operatively connecting the other end of said thermally responsive element to said means for resisting opening movement of said draft

control element to increase the resistance of said draft control element to opening movement in accordance with increase in the temperature in said member effective on said thermally responsive element.

13. In an automatic thermally responsive draft regulator for a combustion heater, a smoke flue having an opening in the wall thereof, a draft control device provided with a draft control member regulating the heater draft, a thermally responsive element located in said opening in the wall of the smoke flue of the heater, said thermally responsive element being a blade-like structure disposed to constitute a closure means for said opening, said element being subject directly on one side thereof to the temperature of the flue gases internally of the flue and on the other side to the temperature of the atmosphere externally of the flue, and means operatively connecting said thermally responsive element to said draft control member to regulate said member in accordance with the temperature in said flue effective on said element.

14. An automatic thermally responsive draft control device comprising, in combustion with a smoke flue, a draft control housing communicating with the flue, means to prevent swirling of air entering said housing into said flue in the direction of the heater attached thereto, a draft control member pivoted in said housing, said draft control member to be opened by excess of outside atmospheric pressure over inside flue pressure, means for effecting a closing torque on said draft control member, a thermally responsive bimetallic element disposed between the heater and housing and fixedly secured at one end to the flue, and means connected to said element and draft control member to vary the torque on the latter in response to thermally induced movement of the former.

15. In combination with a smoke flue of a combustion apparatus, a draft control associated with said flue and comprising a gate mounted to be opened by excess of outside atmospheric pressure over inside flue pressure and provided with normal closing torque means, said smoke flue having an opening in the wall thereof in advance of the inlet from said gate, a blade-like thermal responsive element disposed in said opening and subject on its inner side to the temperature within the flue and on its outer side to the temperature without the flue, there being air inlet spaces at the longitudinal edges of said thermal responsive element, said thermal responsive element being secured to the said flue at one end thereof, an arm pivotally mounted on said flue and secured to the other end of said thermal responsive element whereby the arm is swung on its pivot with the flexing of said thermal responsive element, a shiftably mounted counterweight operatively associated with said gate, and operating connections for said arm to said shiftable weight.

16. In combination with a heater device discharging combustion gases, a draft control associated with said device and comprising a gate mounted to be opened by excess of outside atmospheric pressure over inside flue pressure and provided with closing torque means, said device having an opening therein in advance of the inlet thereto from said gate, a thermal responsive element disposed in said opening and subject on one side to the temperature within the device and on its other side to the temperature without, said thermal responsive element being secured to said device at one end thereof, an arm pivotally

mounted on said device and secured to the other end of said thermal responsive element whereby the arm is swung on its pivot with the flexing of said thermal responsive element, and operating connections for said arm to said gate closing torque means whereby the closing torque is varied as the temperature within and without the device is varied.

17. In combination with the smoke flue of an oil burning apparatus, a draft control associated with said flue and comprising a gate mounted to be opened by excess of outside atmospheric pressure over inside flue pressure and provided with closing torque means, said smoke flue having an opening in the wall thereof, a thermal responsive element disposed in said opening and subject on one side to the temperature within the flue and on its other side to the temperature without the flue, and operating connections for said thermal responsive element to said gate closing torque means to increase the closing torque on the gate as the flue temperature rises, whereby differences between outside atmospheric pressure and inside flue pressure, on said gate, may effect automatic opening and closing of the same at relatively high temperatures of the flue gases as well as at relatively low temperatures of said gases.

18. In combination with the flue of a combustion apparatus, a draft control associated therewith and comprising a housing opening to the flue, a gate swingably mounted in said housing to be opened by excess of outside atmospheric pressure over inside flue pressure and provided with variable closing torque means, said flue having an opening therein, a thermal responsive element disposed in said opening to be subject on its inner side to the temperature within the flue and on its outer side to the temperature without the flue, louvers disposed at the delivery end of said housing to deflect air passing therethrough rearwardly in the flue and away from the said thermal responsive element, and operating connections for said thermal responsive element to said variable closing torque means for said gate.

19. In combination with the flue of a combustion apparatus, a draft control associated therewith and comprising a gate mounted to be opened by excess of outside atmospheric pressure over inside flue pressure and provided with normal closing torque means, said flue having an opening therein, a thermal responsive element disposed in said opening to be subject on its inner side to the temperature within the flue and on its outer side to the temperature without the flue, a movably mounted weight operatively connected to the gate, and operating connections for said thermal responsive element to said weight to increase the closing torque on the gate as the flue temperature rises, whereby differences between outside atmospheric pressure and inside flue pressure, on said gate, may effect automatic opening and closing of the same at relatively high temperatures of the flue gases as well as at relatively low temperatures of said gases.

20. In combination with the flue of a combustion apparatus, a draft control associated therewith and comprising a gate mounted to be opened by excess of outside atmospheric pressure over inside flue pressure and provided with closing torque means including a weight, said flue having an opening therein, a thermal responsive element disposed in said opening to be subject on its inner side to the temperature within the flue and on its outer side to the temperature without the flue, and operating connections for said thermal re-

sponsive element to said weight to increase the closing torque on the gate as the flue temperature rises, whereby differences between outside atmospheric pressure and inside flue pressure, on said gate, may effect automatic opening and closing of the same at relatively high temperatures of the flue gases as well as at relatively low temperatures of said gases.

21. In combination with a combustion apparatus discharging products of combustion, a draft control associated therewith and comprising a gate mounted to be opened by excess of outside atmospheric pressure over inside flue pressure and provided with closing torque means, a thermal responsive element disposed along one side of said combustion apparatus to be subject on its inner side to the temperature within the apparatus and on its outer side to the temperature without, and operating connections for said thermal responsive element to said gate to increase the closing torque on the gate as the flue temperature rises, whereby differences between outside atmospheric pressure and inside flue pressure, on said gate, may effect automatic opening and closing of the same at relatively high temperatures

of the flue gases as well as at relatively low temperatures of said gases.

22. In an automatic thermally responsive draft control, in combination with a smoke flue, a draft control device having a passageway to said flue, a gate pivotally mounted in said passageway to be opened by excess of outside atmospheric pressure over inside flue pressure, means for effecting increasing closing torque on said gate as the flue temperature rises, said means including a rocker member and a compensating weight mounted on said rocker member for movement towards and from the pivotal axis of the rocker member for increasing and decreasing the closing torque on said gate, thermally controlled means disposed to be subject to the temperature of the gases passing through the smoke flue, said thermally controlled means being connected to said compensating weight to move the same towards and from said pivotal axis, whereby differences between outside atmospheric pressure and inside flue pressure, on said gate, may effect automatic opening and closing of the same at relatively high temperatures of the flue gases as well as at relatively low temperatures of said gases.

EDWARD A. FIELD, JR.
